SET SHIFT DEVICE

Hendrik van Doorne and William Gerard Sanders,
Amsterdam, NetherlandsApplication March 7, 1947, Serial No. 733,220
In the Netherlands February 13, 1946

5 Claims. (Cl. 33—110)

1

The invention relates to an apparatus for moving a ruler, triangle, curve or the like each time over a predetermined distance which apparatus comprises at least one foot supported on the surface of the drawing and vertically movable in respect of a slide carrying a fulcrum for an L-shaped lever, one arm of which lever cooperates with the foot and the other arm of which may be operated against the action of a spring by means of an operating member.

With a known embodiment of such a drawing apparatus the slide is movable perpendicularly in respect of the plane of the drawing, while the foot is mounted displaceably in a direction parallel to said plane.

Hence the whole construction was very complicated, needing a large number of elements.

The invention improves this known type of drawing apparatus by the feature that the foot is mounted to the slide so as to be vertically movable in respect of the surface of the drawing, said slide being displaceable in a direction parallel to the surface of the drawing.

In this manner the construction is very much simplified so that only a small number of elements has to be used.

Owing to the fact that the slide is movable in a direction parallel to the plane of the drawing the operating member for the apparatus can be formed by a wall portion of the knob of the apparatus.

The principle according to the invention, also permits of an embodiment constructed in such a way that the distance over which the slide is movable may be adjusted by means of a rotatable ring mounted parallel to the plane of movement of the slide, the inner rim of which ring curves helically inwards in a certain sector of the ring.

The slide may consist of a guide block for a pin of the foot, which block is provided with flanges, which below the edges of a groove engage with a horizontal guide plate, a locking washer being provided above the edges of the groove, which washer is kept in place by means of safety springs resting against the guide block, said slide preferably comprising a pointed portion, which cooperates with the inwardly curving part of the adjusting ring.

The invention will now be further explained with the aid of the accompanying drawing in which:

Fig. 1 is a vertical section through a knob containing a device according to the invention,

Fig. 2 is a plan view of the ring for adjusting the distance between the hatching lines,

2

Fig. 3 a longitudinal section of another embodiment of the slide, and

Fig. 4 is a view similar to Fig. 1 showing a modification.

5 In the said drawing the reference numeral 1 denotes a knob which may be attached e. g. to a drawing triangle.

In this knob there is provided a space 2 in which the device according to the invention is lodged.

An operating member 4 to which there is attached a rod 5 extends through a lateral recess 3 of the knob. This rod cooperates by means of a stud with the forked end of a lever 6 which is 15 pivotally mounted at 7 on a block 8. This block is located on a plate 9 of a slide. Under the plate there is provided an intermediate plate 10 which is adapted to be shifted in a slot 11 of the guide plate 12. The two plates 9 and 10 are fixed to the lower plate 13. Secured to the knob in any desired way below the slide 12 and spaced therefrom to form a guideway for the plate 13 are blocks 37 and 38. The plates 12 and 25 may be secured by screws or in any other way to the knob.

25 The short lever arm also co-operates by means of a stud and fork connection with the pin 14 which is attached to ribbed foot 16. This pin passes through a sleeve 15 which is attached to the slide.

30 The long arm of the lever is supported against a hinge ball 17 of a rod 18 which is shiftable in a sleeve 19. The said sleeve and rod are surrounded by a press spring 20, which on one side is held by a ring 21 and on the other side by a screw head 22 of the sleeve 19.

35 The screw head 22 may be screwed into and out of a threaded sleeve 23, whereby the tension of the spring 20 may be controlled.

In the same plane as that of the plate 9 there is provided a ring 24 (see also Fig. 2) which is 40 guided by a ring 25 a fourth part of which has been removed.

The ring 24 is rotatable by means of a handle 26 which also serves as a pointer for indicating the width of the distance between the hatching on a scale not represented in the drawing.

45 The plate 9 has a pointed end 27 which cooperates with a helically shaped portion, or a portion that is gradually curved inward in some other manner, 28 of the ring 24.

50 By turning the ring 24, the point 27 and, along with the same, the slide 9, 10 will be hampered in its return movement.

The device operates as follows:

55 The draftsman holds the knob in his left hand

and with his left thumb presses the operating member 4 inwardly in the direction of the arrow a. This will cause the lever 6 to turn to the left whereby the stud 14 is pressed down. The ribbed foot will then be pressed into the paper 29. At this moment the rotating motion of lever 7 will be stopped and the said lever will tend to move to the left with regard to the knob 1 under the influence of the pressure exerted on the member 4.

As this is impossible, because the foot 16 is firmly pressed into the surface of the paper, the knob 1 as well as the ruler or triangle 30 attached to the same will be shifted to the right, until the plate 10 has reached the left hand end of the slot 11.

If the draftsman releases the operating member 4, the lever 7 will be returned to its original position by the spring and will then carry along the foot 16. As soon as the return movement of the foot has been stopped, the slide is also returned to its initial position by means of the spring. During this movement the point 21 of the plate 9 will contact with the segment 28, whereby the width of the distance between the hatching lines will be determined.

By the movements described above the drawing instruments in or on which the knob provided with the device according to the invention is attached, are successively lifted a small distance off the surface of the drawing and subsequently moved over the predetermined distance in the direction of the arrow b and then lowered again onto the surface of the drawing, after which the hatching line is drawn. The said movements are then repeated.

With the embodiment according to Fig. 3, the slide consists of the two outer plates 9 and 13 which are located one on each side of the guide plate 12. A block 31 extends through the slot 11 in the said guide plate which block is provided with a recess 32 for the pin of the foot.

The plates 9 and 13 are pressed against the plate 12 by means of springs 33 in order to prevent any possible play, so that the movement of the slide will be constant.

The plates 9 and 13 are held on one side by the flange 35 of the block 31 and on the other side by the springs 33.

In the plates 9 and 13 there is provided an opening forming a passage for the block.

This embodiment is very suitable for mass production.

Fig. 4 of the drawing represents an embodiment provided with a tension spring 34, which embodiment is very simple and reliable and requires only a very small number of members.

We claim:

1. An apparatus for moving a ruler, triangle, curve or the like a predetermined distance comprising a slide, a foot supported on the surface of a drawing vertically movable with respect to said slide and mounted on said slide to be vertically movable with respect to the surface of said drawing, an L-shaped lever fulcrumed on said slide, one arm of said lever cooperating with said foot, a spring biasing the other arm of said lever, an operating member for operating said other arm against said spring and said slide being displaceable in a direction parallel to the surface of said drawing.

2. An apparatus as set forth in claim 1 wherein said operating member is formed as a side of said apparatus.

3. An apparatus as set forth in claim 1 wherein a ring rotatably mounted parallel to the plane of movement of said slide having a helical inner periphery cooperable with said slide adjusts the displacement of said slide.

4. An apparatus as set forth in claim 1 wherein a pin is provided on said foot and said slide consists of a guide block for said pin, said block having flanges which below the edges of a groove engage with a horizontal guide plate, a locking washer being provided above the edges of the groove, which washer is kept in place by means of safety springs resting against the guide block.

5. An apparatus as set forth in claim 3 wherein the slide comprises a pointed portion which cooperates with the helical periphery of the adjusting ring.

HENDRIK VAN DOORNE,
WILLIAM GERARD SANDERS.
